[57] **CLAIM**

The ornamental design for a big button telephone, as shown and described.

DESCRIPTION

FIG. 1 is a perspective view of the handset of a big button telephone showing our new design;

FIG. 2 is a rear plan view of the handset of FIG. 1;

FIG. 3 is a right side elevation view of the handset of FIG. 1;

FIG. 4 is a front plan view of the handset of FIG. 1;

FIG. 5 is a left side elevation view of the handset of FIG. 1;

FIG. 6 is a top plan view of the handset of FIG. 1;

FIG. 7 is a bottom plan view of the handset of FIG. 1;

FIG. 8 is a perspective view of the handset in place on the base unit of the big button telephone;

FIG. 9 is a top perspective view of the base unit of FIG. 8;

FIG. 10 is a top plan view of the base unit of FIG. 9;

FIG. 11 is a left side elevation view of the base unit of FIG. 9, the right side elevation view being a mirror image;

FIG. 12 is a bottom plan view of the base unit of FIG. 9;

FIG. 13 is a front elevation view of the base unit of FIG. 9; and,

FIG. 14 is a rear elevation view of the base unit of FIG. 9.

The handset and base have been shown separately in FIGS. 1-7 and 9-14 for convenience of illustration.
